UNITED STATES PATENT OFFICE.

GEORGE W. WEMPLE, OF BOSTON, MASSACHUSETTS.

BOWLING-ALLEY.

SPECIFICATION forming part of Letters Patent No. 627,712, dated June 27, 1899.

Application filed November 14, 1898. Serial No. 696,405. (No model.)

To all whom it may concern:

Be it known that I, GEORGE W. WEMPLE, of Boston, in the county of Suffolk and State of Massachusetts, have invented certain new and useful Improvements in Bowling-Alleys, of which the following, taken in connection with the accompanying drawings, is a specification.

My invention relates to bowling-alleys, and has for its object a reduction in the cost of operating the same; and it consists in certain novel features of construction, arrangement, and combination of parts, which will be readily understood by reference to the description of the accompanying drawings and to the claims hereto appended and in which my invention is clearly pointed out.

Figure 1 of the drawings is a plan of a portion of a bowling-alley embodying my invention and showing six of the pins in raised or standing positions and four pins in fallen or depressed positions with a portion of the cover of the said frame removed. Fig. 2 is a sectional elevation of the same, except that all the pins are standing, the cutting-plane being on line 2 2 on Fig. 1. Fig. 3 is a side elevation with all the pins standing. Fig. 4 is a section on line 3 3 on Fig. 1, looking toward the left of Fig. 1. Fig. 5 is a section on line 4 4 on Fig. 1. Fig. 6 is a section on line 5 5 on Fig. 1, looking toward the left of said figure. Fig. 7 is a section on line 6 6 on Fig. 1, looking toward the left of said figure; and Fig. 8 is a partial section on line 7 7 on Fig. 1.

In the drawings, A is the alley proper, B the gutters on each side of the alley, and H the partition-boards between two adjacent alleys, all of well-known construction.

D is an abutment extending transversely across the rear end of the alley and gutters and has set in or secured to its front side elastic cushions a, a, and b, composed of rubber centers covered with envelops c, of felt or other suitable material, as shown in Figs. 5 and 7.

E is a rectangular chambered structural frame supported over the rear ends of said alley A and gutters B, the bottom of which is slightly downwardly inclined from the front toward the rear, and at a distance above the upper surface of said alley, at its lowest part, somewhat greater than the diameter of the

ball to be used, which may be larger or smaller, but a four-and-one-half-inch ball is preferable. The chamber of said frame is divided into a series of compartments E¹, E², E³, E⁴, E⁵, E⁶, E⁷, E⁸ and E⁹ by vertical partitions d, d¹, d², d³, d⁴, d⁵, d⁶, and d⁷, as shown in Fig. 1. In suitable bearings in said partitions is mounted a rod e, which extends through all of said partitions and has mounted thereon the pins e¹, e², e³, and e⁴ and the short levers f, f¹, and f², all so arranged as to be independently movable about said rod. Another rod g extends through the partitions d¹, d², d³, d⁴, d⁵, and d⁶ and has mounted thereon the pins e⁵, e⁶, and e⁷, and a rod g¹ is mounted in bearings in the partitions d², d³, d⁴, and d⁵ and has mounted thereon the pins e⁸ and e⁹, and a rod g², mounted in bearings in the partitions d³ and d⁴, has mounted thereon the pin e¹⁰.

The pin e⁵ is connected at its lower end by the links h to the lower end of the dummy lever f, and in like manner the pins e⁶ and e⁷ are connected to the dummy levers f¹ and f², respectively.

The pins e² and e⁸ have their lower ends connected together by the link h¹, and the pin e¹⁰ has set in its lower end a stud i, which projects laterally therefrom through the curved slot i¹ in the partition d³ and has connected thereto one end of the link h², the opposite end of which is connected to the lower end of the pin e² in such a manner that when the ball is so rolled as to knock down the pin e² the pins e⁸ and e¹⁰ will fall at the same time.

The lower end of the pins e³ and e⁹ are connected together in the same manner as the pins e² and e⁸, so that they must both fall together.

F is a rod extending transversely through all of the partitions from d to d⁷, upon which is mounted, so as to be freely movable about its axis, a series of trip-levers F', corresponding in number to the number of the compartments E² to E⁸ and arranged normally in an inclined position, with their rear ends projecting below the bottom of the said frame in positions to be struck by the ball when rolled beneath them, and thus cause said rear ends to be raised and act upon one of the pins to cause it or it, with others, to fall into

the inclined position shown in the left portion of Fig. 1.

The rear ends of the trip-levers F' have their under sides padded and covered with 5 felt to prevent noise and injury to the ball, as shown in Figs. 4, 5, and 6.

Each of the trip-levers F' has secured to the upper side of its rear arm an upwardly and forwardly curved spring j, and each of 10 the pins e', e², e³, and e⁴ and the short levers or dummies f', f², and f³ have secured to the front sides of their lower arms the rearwardly curved springs j', the convex sides of said springs j and j' being in near proximity to 15 each other when the pins are set up, so that when the ball is rolled beneath any one of the said trip-levers and lifts its rear end the spring j, acting upon the spring j' with a yielding pressure, moves the pin to which said 20 spring j' is secured about the rod e and causes it to fall toward the front into the inclined position shown in Figs. 4, 5, 6, and 7.

G is a rocker-shaft mounted in bearings in the partitions d to d' and having firmly secured thereon the arms k, k', and k'', the free ends of which carry the rod k'', which when raised by a partial rotation of the shaft G acts upon the pins e', e², e³, and e⁴ and the dummies f', f², and f³ to raise them, and through them 30 all the other pins, into a standing position slightly inclined toward the rear from a perpendicular, in which positions said pins and levers abut against the rear ends of the slots in the top covering I of said frame E, as shown 35 in Figs. 4, 5, and 6.

The rocker-shaft G has secured to one end thereof the lever G', to the movable end of which is connected one end of the coiled spring G², the other end of which is connected to the cord or chain G³, which passes upward over the sheave g³ and forward to the front end of the alley, where it is connected to the hand-lever G⁴, hinged to the upper edge of the partition-board H at the outer side of 45 the gutter B, as shown in Fig. 3.

The lever k has a short arm k', to the free end of which is pivoted one end of the link l, the opposite end of which is pivoted to the movable end of the arm l', firmly secured to 50 the end of the rocker-shaft l'', mounted in suitable bearings in said partitions d to d' and having set in or secured to its upper side as many trip-arms l³ as there are compartments between the partitions d and d'.

55 A rod m extends through the partitions d to d' and has suspended therefrom in each compartment E² to E⁴ a locking-plate m', the lower end of which is pressed toward the rear by the spring m², set in the rod m³, so that 60 when the front end of a trip-lever F' is depressed by the ball coming in contact with its rear padded end the lower end of the plate m' is moved over the front end of said trip-lever F' and locks it in said depressed position, in which position said parts remain until the rod k³ is again raised to set up the pins by the operation of the hand-lever G⁴, when

the trip-arm l³ moves the lower end of the plate m' toward the front and releases the trip-lever F'.

The partitions d to d' have slots n formed in their upper edges, in the bottoms of which the rod k³ rests when in its normal position, and the cover I of the said frame E is slotted to allow the upward passage of said rod k³ 75 when it is desired to raise or set up the pins.

J is an elbow-lever fulcrumed at the end of its horizontal arm within the compartment E³, with its other arm projecting upward to the upper side of the cover I of the structural frame E and having secured therein at its bend the rod J', which extends through slots J² in the partitions d to d' and is connected at its ends to the front ends of the levers J³, firmly secured near the middle of their lengths 80 upon the rocker-shaft K, the rear arms of said levers J³ being weighted to counterbalance said rod J', so as to normally maintain said rod in its raised position, as shown in Figs. 4, 5, 6, and 7. The lower ends of the pin e⁶ 90 and the short dummy lever f' being connected together by the links h³, as set forth, when the ball strikes the trip-lever F' in the compartment E⁵ the upward movement of its rear end causes the spring j thereon to act upon the spring j' on the dummy lever f' to cause it and the pin e⁶ to fall, and the heavy pin e⁶, the upper end of which is weighted with lead o, falling upon the upper end of the bent lever J, depresses the rod J' and the front ends of all of the trip-levers F', thereby causing all of the pins to fall and producing a ten-strike. In like manner the pins e⁵ and e⁷ being 95 respectively connected by links h to the dummy levers f and f², and there being just above the levers F' in the compartments E³ and E⁷ the pivoted levers or plates L, having set in their front ends the horizontal rods p, which project therefrom through slots p' 100 in the partitions separating said compartments from those upon each side thereof and over the trip-levers F' in said contiguous compartments, if the ball is rolled so as to come in contact with the trip-lever F' in the compartment E³ and cause the pin e⁵ to fall it 105 strikes upon the arm L', projecting upward from the pivoted plate L, and depresses the forward end thereof, causing it to engage the trip-lever beneath it and the rod p to engage the trip-levers in the compartments E² and E⁴, depressing said three trip-levers and insuring the falling of the five pins e', e², e³, e⁸, and e¹⁰, and if the ball strikes the trip-lever F' that is located in the compartment E⁷, the four pins e³, e⁴, e⁷, and e⁹ will fall. If the ball is so rolled as 115 to strike only the trip-lever F' located in the compartment E² or E⁴ only one pin will fall, or if the ball is so rolled as to strike only the trip-lever F' located in the compartment E² or E⁴ two or three pins, respectively, will fall. 120 If, however, the ball is so rolled as to come in contact with the two trip-levers F' located in the compartments E³ and E⁴ five pins will fall, and if the ball is so rolled as to contact

With the two trip-levers located in the compartments E⁶ and E⁷ or E⁷ and E⁸ four pins will fall.

5 Mis a wooden rod or bar extending through the several compartments E to E⁸ and has secured thereon in each compartment a cushion r of felt to limit the upward movements of the rear ends of the trip-levers F' and diminish the shock of the blow thereof. A felt cushion r' is also provided beneath the front end of each trip-lever F', as shown in Figs. 4, 5, and 6.

10 Stop-bars s, s', and s² extend across the various compartments at the upper edges of the partitions d' to d⁷ and have secured to their upper sides felt cushions t to limit the downward movements of the pins e' to e¹⁰ and diminish the shock of the blow produced thereby.

15 20 An elastic arm u, preferably of rubber, is pivoted to the front of the frame E by the clamp u' in line with the center of the compartment E⁵, which normally remains in the pendent position shown in Figs. 2, 5, 6, and 25 7, in which position it tends to deflect the ball to the right or left if it is struck thereby in any other way than directly in its center; but when not desired it may be turned upward into a horizontal position, where it cannot 30 be struck by the ball, as shown in Figs. 3 and 4. The ball after acting upon a trip-lever F comes in contact with the cushion b, or if it misses the trip-levers F and falls into the gutter B it comes in contact with the 35 cushions C, and in either case the reaction of said cushions causes the ball to be returned to the front end of the alley. When the player has completed his turn, a proper forward movement of the hand-lever will set up 40 all of the fallen pins, whether all or only a portion of them are down.

45 By the use of my invention the services of a man or boy to set up the pins and return the balls is rendered entirely unnecessary, and a considerable saving in time is made, which is lost while waiting for the pins to be set up in the old way.

50 What I claim as new, and desire to secure by Letters Patent of the United States, is—
50 1. In a bowling-alley the combination of the ball-rolling surface or alley proper; a chambered frame located above said alley with its bottom at a distance from said alley somewhat greater than the diameter of the ball to be used; a series of tenpins carried by said frame with their lever ends within said chambered frame and their main bodies projecting above said frame, and arranged to fall from a nearly perpendicular position to a nearly horizontal position; a series of seven trip-levers pivoted to said frame with their rear ends normally below the bottom of said frame and in close proximity to each other; and means intervening between said trip-levers and pins 65 whereby an upward movement of the rear end of one of said trip-levers caused by the con-

tact of the ball therewith will cause one or more of said pins to fall.

2. In a bowling-alley the combination with a ball-rolling surface or alley proper, of a 70 chambered frame supported above said alley with its bottom at a distance from said ball-rolling surface somewhat greater than the diameter of the ball to be used; a series of tenpins arranged in the usual order relative to 75 each other and pivoted to said frame so as to be movable about said pivotal connection from a nearly-horizontal position to a position slightly inclined to the rear from a perpendicular position; a series of seven trip-levers 80 pivoted within said frame with their rear ends projecting below the bottom of said frame and in close proximity to each other so that a ball rolled along the surface of the alley to the rear end thereof will contact with and raise 85 the rear end of one or more of said trip-levers; and means interposed between said pins and levers whereby the passage of a ball beneath said frame to the rear of said alley will cause 90 one or more of said pins to fall.

3. The combination of a ball-rolling surface or alley; a series of tenpins arranged in the usual order relative to each other; three dummy levers alternating with the pins in the rear row, said pins and dummies being permanently mounted upon pivotal axes; a chambered frame for supporting said pins and dummies, supported above said alley with its bottom at a distance therefrom somewhat greater than the diameter of the ball to be used; a 95 downwardly-projecting curved spring secured to the lower end of each of said tenpins and dummies; a series of seven trip-levers pivoted within said frame with their rear ends normally projecting below the bottom of said 100 frame to a point distant from the alley-surface less than the diameter of the ball to be used; and an upwardly and forwardly curved spring secured to the upper surface of the rear end of each of said trip-levers, with its 105 convex surface in close proximity to the convex surface of the spring on one of the pins or a dummy in such a manner that when one of said trip-levers is struck by a ball and moved about its pivot its spring acting upon 110 the spring on the pin or dummy imparts an elastic or yielding pressure to said pin or dummy to cause it to fall.

4. The combination in a bowling-alley, of a ball-rolling surface or alley; a chambered 120 frame divided into a series of compartments and supported above said alley-surface with its under side at a distance above said alley somewhat greater than the diameter of the ball to be used; a series of tenpins pivoted 125 near their lower ends in said compartments with the greater part of their lengths projecting above said frame and three dummy levers pivotally mounted on said frame between the pins in the rear row; a series of seven trip-levers pivotally mounted in said compartments 130 normally in an inclined position with their rear

ends projecting below the bottom of said frame to a point distant from the alley-surface less than the diameter of the ball to be used and in close proximity to each other; means intervening between said trip-levers and pins and dummies whereby an upward movement of the rear end of a trip-lever will cause one or more of said pins and dummies to fall; and an elastic cushion at the rear end of the alley for automatically returning the ball to the front end of the alley.

5. The combination in a bowling-alley of a ball-rolling surface; a pin-supporting frame supported above said surface with its bottom 15 at a distance from said surface somewhat greater than the diameter of the ball to be used; the series of pins e' , e^2 , e^3 , e^4 , e^5 , e^6 , e^7 , e^8 , e^9 , and e^{10} , pivotally mounted in said frame, the three dummies f' and f^2 pivotally mounted 20 in said frame between the pins e' , e^2 , e^3 , and e^4 ; the links h , h , connecting the lower ends of the dummies f' and f^2 to the lower ends of the pins e^5 and e^7 respectively; the links h' connecting the lower ends of the pins e and e^8 25 with the lower ends of the pins e^8 and e^9 ; the link h^2 connecting one of the pair of pins e^2 e^8 to the pin e^{10} ; the links h^3 connecting the lower end of the dummy f' to the lower end of the pin e^6 ; a series of trip-levers pivotally mounted 30 in said frame one beneath each of the pins e' e^2 e^3 and e^4 and each of the dummies, with their rear ends projecting below the bottom of said frame to a level distant from said ball-rolling surface less than the 35 diameter of the ball to be used, and in close proximity to each other; and spring-contact arms on said trip-levers the pins e' e^2 e^3 and e^4 and the dummies f' and f^2 all constructed, arranged and operating substantially as described.

6. The combination in a bowling-alley, of a ball-rolling surface; a pin - carrying chambered frame supported above said ball-rolling surface, with its bottom at a distance 45 from said surface greater than the diameter of the ball to be used and divided into a series of compartments; a series of seven trip-levers pivotally mounted in as many of said compartments, one in each, in inclined positions with their rear ends projecting below the bottom of said frame and to a level above said ball-rolling surface a distance less than the diameter of the ball to be used; the ten-pins e' , e^2 , e^3 , e^4 , e^5 , e^6 , e^7 , e^8 , e^9 , and e^{10} , and 55 the dummies f' , f^1 , f^2 , all pivotally mounted in said frame; the curved springs j on said trip-levers; the curved springs j' on the pins e' , e^2 , e^3 , and e^4 , and the dummies f' and f^2 ; the links h connecting the dummy f' and the 60 pin e^5 ; the links h' , and h^2 connecting the pins e^2 , e^8 , and e^{10} ; the plate L provided with the upwardly - projecting arm L' pivotally mounted beneath the pin e^5 and dummy f' in position to contact with a trip-lever; and rod 65 p set in its front end and projecting from both edges of said plate into positions to contact with the trip-levers in the next compart-

ment on each side of the one in which said plate is mounted all constructed arranged and operating substantially as described for 70 the purpose specified.

7. The combination in a bowling-alley, of a ball-rolling surface; a pin-carrying chambered frame divided into a series of compartments and supported above said surface with its bottom sufficiently removed from said surface to permit the passage of the ball between said surface and frame; a series of seven trip-levers pivotally mounted in said compartments in inclined positions with their rear ends projecting into the space between said frame and said ball-rolling surface to a level distant from said surface less than the diameter of the ball to be used; the tenpins e' , e^2 , e^3 , e^4 , e^5 , e^6 , e^7 , e^8 , and e^{10} , and the dummies f' , f^1 , f^2 , all pivotally mounted in said frame; the curved springs j on said trip-levers; the springs j' on said dummies and the pins e' e^2 e^3 and e^4 ; links connecting the dummy f^2 and the pin e^7 ; links connecting the pins e^8 and e^9 ; the pivoted plate L provided with the upwardly-projecting arm L' and the rod p set in its front end and projecting laterally therefrom as shown, said plate being mounted in the compartment beneath the pin e^7 and the dummy f^2 and 95 adapted to be acted upon by the pin e^7 to move it into contact with and vibrate the trip-lever beneath it and one on each side thereof and thus insure the falling of the four pins e^8 e^4 e^7 and e^9 substantially as described. 100

8. The combination in a bowling-alley of a ball-rolling surface; a chambered pin - supporting frame arranged above said surface with its bottom at a distance therefrom greater than the diameter of the ball to be used; a series of tenpins e' , e^2 , e^3 , e^4 , e^5 , e^6 , e^7 , e^8 , e^9 , and e^{10} , and the dummies f' and f^2 all pivoted to said frame; a series of seven trip-levers pivotally mounted in said frame beneath the pins e' e^2 e^3 and e^4 and said dummies, with their rear ends projecting below the bottom of said frame into positions to be struck by a ball rolled beneath them on the alley; the springs j secured on said levers; the springs j' secured on the pins e' , e^2 , e^3 , and e^4 , and on the dummies f' , f^1 , f^2 ; the bent lever J pivotally mounted beneath the pin e^6 ; the two-armed weighted levers J^3 ; the rocker-shaft K upon which said levers J and J^3 are mounted; and the rod J' connecting the movable ends of said lever J^3 110 and the elbow of the lever J and arranged to bear upon and depress all of said trip-levers, when the pin e^6 falls upon the upper end of the lever J , and thus cause all of said pins to fall. 115

9. The combination in a bowling-alley, of a ball-rolling surface; a chambered frame arranged above said surface with its bottom at a distance therefrom greater than the diameter of the ball to be used; a series of tenpins e' , e^2 , e^3 , e^4 , e^5 , e^6 , e^7 , e^8 , e^9 , and e^{10} , and the dummy levers f' , f^1 , and f^2 , all pivotally mounted upon said frame; a link connecting the dummy f to the pin e^5 ; links connecting 120

- the pins e^2 , e^8 , and e^{10} ; a link connecting the dummy f' to the pin e^6 ; a link connecting the pin e^8 to the pin e^9 ; a link connecting the dummy f^2 to the pin e^7 ; a series of trip-levers 5 F' pivotally mounted in said frame beneath the pins e' , e^2 , e^8 and e^4 and the dummies f , j' , and f^2 , with their rear ends projecting below the bottom of said frame into positions to be struck by a ball rolled beneath said frame on 10 said ball-rolling surface or alley; a spring j secured to the rear end of each of said trip-levers; a spring j' mounted upon each of said dummies and the pins e' , e^2 , e^8 and e^4 ; the rocker-shaft G ; a plurality of arms firmly secured upon said shaft the rod k^3 connecting the movable ends of said arms in a position to act upon said dummies and the pins e' , e^2 , e^8 , and e^4 , or any of them that are in a fallen position to raise them; the lever G' firmly secured upon the end of said shaft G ; the hand-lever G^4 located at the front end of the alley; and means connecting said hand-lever with the movable end of the lever G' whereby a forward movement of the hand-lever will 25 cause an upward movement of the rod k^3 and a consequent raising of all fallen pins.
10. The combination of a ball rolling or alley surface; a chambered frame arranged above said alley-surface with its bottom at a 30 distance therefrom greater than the diameter of the ball to be used; a series of tenpins and three dummies pivotally mounted in said frame; a series of trip-levers pivotally mounted in said frame beneath said dummies and the rear row of said pins; contact-springs on 35 said dummies and rear row of pins and on the rear ends of said trip-levers as set forth; a series of locking-plates m' each arranged and adapted to engage the front end of one of said trip-levers when depressed; springs 40 to move said locking-plates into engagement with said trip-levers to lock them; the rocker-shaft l^2 provided with arms l^3 corresponding in number to the plates m' ; and means for oscillating the shaft l^2 to move said plates m' 45 toward the front and unlock said trip-plates.
11. In a bowling-alley having a series of tenpins pivotally mounted upon a frame raised above the ball-rolling surface the combination with said pins of trip-levers pivotally mounted in said frame in positions to be struck by the ball when rolled along said surface means intervening between said levers and pins whereby the upward movement of the rear end of a trip-lever will cause one or 50 more of said pins to fall; and the pendent elastic arm u pivotally secured to the front of said frame directly above the center longitudinal line of the alley as and for the purpose described.
- In testimony whereof I have signed my name to this specification, in the presence of two subscribing witnesses, on this 7th day of November, A. D. 1898.
